BOTTLE OR THE LIKE

Gerald Hoffman, Beverly Hills, Calif., assignor to
Louis Milani Foods, Inc., Maywood, Calif., a corporation of Illinois

Application September 2, 1949, Serial No. 4,831

Term of patent 14 years

(Cl. D58—8)

To all whom it may concern:

Be it known that I, Gerald Hoffman, a citizen of the United States, residing at Beverly Hills, in the county of Los Angeles and State of California, have invented a new, original, and ornamental Design for a Bottle or the like, of which the following is a specification, reference being had to the accompanying drawings, forming part thereof.

In the drawing:

I claim:

The ornamental design for a bottle or the like, substantially as shown.

GERALD HOFFMAN.
